TOY ROBOT FIGURE

Nicholas V. Lackovic, Pittsburgh, Pa., assignor to Wolverine Supply and Manufacturing Company, Pittsburgh, Pa., a corporation of Pennsylvania

Application December 19, 1955, Serial No. 39,380

Term of patent 14 years

(Cl. D34—15)

Fig. 1 is a front elevational view of a toy robot figure, showing my new design;

Fig. 2 is a side elevational view thereof; and

Fig. 3 is a top plan view thereof.

I claim:

The ornamental design for a toy robot figure, as shown.
